UNITED STATES PATENT OFFICE.

WILLIAM HUMANS, OF CAMBRIDGE, MASSACHUSETTS, ASSIGNOR TO THE AMERICAN MAGNETIC ELECTRIC COMPANY, OF JERSEY CITY, NEW JERSEY.

MAGNETO-ELECTRIC MACHINE.

SPECIFICATION forming part of Letters Patent No. 375,751, dated January 3, 1888.

Application filed July 23, 1885. Serial No. 172,440. (No model.)

To all whom it may concern:

Be it known that I, WILLIAM HUMANS, of Cambridge, in the county of Middlesex and State of Massachusetts, have invented a new and useful Press-Knob Generator, of which the following is a specification, reference being had to the accompanying drawings, in which—

Figure 1 is a plan, Fig. 3 a bottom plan, 10 and Figs. 2 and 4 sections, of one of my generators. Fig. 5 illustrates the construction of the arm for closing the circuit. Figs. 6 and 7 illustrate the construction of the pole-pieces. Figs. 8 and 9 show a modification. Fig. 10 is 15 a perspective detail.

In the drawings, A represents a permanent magnet, which may be of any usual construction; but as shown is fully described in my application, Serial No. 172,432.

20 B is a revolving armature, upon one end of which is the pawl b, which engages with the ratchet b', and this ratchet is fast to the same hub to which pinion b² is fast, the shaft of the armature passing through this hub, so that 25 the pinion b² may revolve in one direction without moving the armature, or the armature may revolve in one direction independently of the pinion. The pinion b² is revolved by the sector D, which is fast to the 30 rock-shaft d. Another arm, d', of rock-shaft d is jointed to the push-pin d², so that when the push-pin is thrust inward the sector D causes the pinion b² to revolve rapidly, and as the pinion b² is then connected by the pawl 35 b and ratchet b' to armature B, that armature is rapidly revolved when the push-pin is forced in, thus generating currents for signalling and other purposes.

When the push-pin d² is inserted through 40 the side of the case, as in Figs. 1 and 4, it may be jointed directly to the arm d' of the rock-shaft; but when the push-pin d² is not crosswise of the rock-shaft some intermediate connection must be used, as in Figs. 8 and 9.

45 This combination of the push-pin with the armature and its pinion, by means of a rock-shaft and sector-gear, constitutes one feature of my invention.

Another feature of my invention is the

spring-arm f for closing the circuits. This 50 arm f is a rod of metal, one part of which extends into the coiled spring f', one end of the coil being fast to it and the other end being fast to the insulating-block f² at the screw-cup f³, by which the coil f' is connected to 55 the circuit. The arm f is held normally out of contact with the pintle f³ on the armature-shaft by the insulator in the end of arm f⁴ of rock-shaft d; but when rock-shaft d is moved on its axis to revolve the armature its arm f⁴ 60 is moved away from arm f, and arm f is pressed against pintle f³, and as one end of the armature-coil is in metallic contact with the shaft of the armature in the usual way the currents generated in the coil go to 65 line through pintle f³, arm f, and coiled spring f'. This is an important feature, for the reason that when a number of press-knob generators are connected to the same pair of conductors each must be in open circuit with 70 the bell or other signal, as otherwise the current would be divided among them all, and that portion of it which went to the signal would be too weak; but when there is but one generator in circuit with the bell no such 75 division takes place, but the full force of the current is properly applied.

Another feature of my invention is the combination of the pole-pieces g g by means of two clamping-disks, g' g', held together by 80 screws or nuts g² g², and recessed in the pole-pieces—that is, each pole-piece is formed with a recess at each end—so that when the disks g' of non-magnetic metal are clamped together, 85 with the pole-pieces between them, the pole-pieces are not only firmly held, but also centered, so that the armature may run close to the inner surface of the pole-pieces without danger of binding. The disks g' not only serve as bearings for the armature-shaft, but 90 also serve as a frame for the rock-shaft d and its connections and the insulating-block f².

What I claim as my invention is—

1. In combination, the armature, its pawl b, ratchet b', pinion b², sector-gear D, rock-shaft d, and press-knob d², substantially as described.

2. The arm f, its spring f', and insulator-

block f^3 , in combination with the arm f^4 of | and its rock-shaft, in combination with arm
rock-shaft d and with the armature and its | f^4 and arm f and its spring, substantially as
shaft, substantially as described. | described.

3. The pole-pieces $g\ g$, recessed as described,
5 in combination with the clamping-disks $g'\ g'$,
as set forth.

4. The armature, its pinion, the sector-gear |
